UNITED STATES PATENT OFFICE

JOHN STERLING GULLBORG, OF CHICAGO, ILLINOIS, ASSIGNOR TO ALEMITE DIE CASTING & MFG. CO., OF WOODSTOCK, ILLINOIS, A CORPORATION OF DELAWARE

DESIGN FOR A HANDLE FOR DOOR OF AUTOMOBILE OR THE LIKE

Application filed September 11, 1930. Serial No. 36,935. Term of patent 3½ years.

To all whom it may concern:

Be it known that I, JOHN STERLING GULLBORG, a citizen of the United States, residing at Chicago, in the county of Cook and State of Illinois, have invented a new, original, and ornamental Design for a Handle for Door of Automobile or the like, of which the following is a specification, reference being had to the accompanying drawing, forming a part thereof.

Fig. 1 is a lateral elevation of a handle for

door of automobile or the like, showing my new design;

Fig. 2 is a plan view thereof; and

Fig. 3 is an end view thereof.

I claim:

The ornamental design for a handle for door of automobile or the like as shown.

In witness whereof, I hereunto subscribe my name this 5th day of September, 1930.

JOHN STERLING GULLBORG.
